O. W. MOORE.

AIR HEATER FOR AUTOMOBILE ENGINES.

APPLICATION FILED FEB. 2, 1920.

1,371,509.

Patented Mar. 15, 1921.

UNITED STATES PATENT OFFICE.

OTIS W. MOORE, OF ALLERTON, ILLINOIS.

AIR-HEATER FOR AUTOMOBILE-ENGINES.

1,371,509.

Specification of Letters Patent. Patented Mar. 15, 1921.

Application filed February 2, 1920. Serial No. 355,638.

To all whom it may concern:

Be it known that I, OTIS W. MOORE, a citizen of the United States, residing at Allerton, in the county of Vermilion and State of Illinois, have invented certain new and useful Improvements in Air-Heaters for Automobile-Engines; and I do hereby declare the following to be a full, clear, and exact description of the invention, such as 5 will enable others skilled in the art to which it appertains to make and use the same.

The present invention relates to a device designed for use with automobile hydrocarbon engines for supplying heated air to the 15 carbureter in order to facilitate starting in cold weather, and it is the object of the invention to provide a novel and improved attachment of that character which is exceedingly simple and inexpensive in construction, which can be readily installed, 20 and which will operate in a simple and effective manner.

With the foregoing and other objects in view, which will be apparent as the description proceeds, the invention resides in the construction and arrangement of parts hereinafter described and claimed, it being understood that changes can be made within the scope of what is claimed without departing 30 from the spirit of the invention.

The invention is illustrated in the accompanying drawing, wherein:

Figure 1 is a diagrammatical view showing the air heater connected to the carbureter, portions being shown in elevation and others in section.

Fig. 2 is an enlarged sectional detail of the means for mounting the heating unit in the air chamber.

40 In the drawing, there is illustrated a conventional carbureter 1 supplying the intake manifold 2 of the engine with carbureted air, and provided with a choke valve 3 in the air inlet port 4, which is operable as usual for choking the entrance of air to increase the vacuum within the carbureter and increasing the flow of gasoline or other fuel.

45 In carrying out the invention, there is provided an air chamber 5 of any suitable size, which is provided with heat insulation to prevent the loss of heat units, and a tube 6 leads from the top of the chamber 5 and is connected to the carbureter 1 at the inner side of the choke valve 3, whereby the heated 55 air will flow from the upper portion of the chamber 5 through said tube into the cham-

ber of the carbureter, when the tube 5 is opened. Said tube is also preferably insulated to prevent the escape of heat and has a shut off valve 7 which can be controlled from 60 the dash of the automobile or other suitable point.

A heating unit 8 is provided within the chamber 5 for heating the air therein, and, as shown, the heating unit is an electric lamp 65 although any other suitable heating unit or resistance element can be used. In the embodiment shown, the lamp 8 constitutes a convenient removable heating unit and will serve the purpose nicely. As shown, a lamp 70 8 is fitted within a lamp socket 9 carried by a removable plug 10 in the bottom of the chamber 5, whereby the plug can be removed for removing the lamp from the casing to replace the lamp when burnt out. The lamp 75 is disposed in an electrical circuit 10 including the battery 12 or other source of electrical energy, and a controlling switch 13. This switch is used for closing the circuit to energize the lamp or heating unit 8, when 80 heated air is to be supplied to the carbureter. The casing or chamber 5 has an air inlet for the entrance of fresh air, and, as shown, this air inlet port 14 extends through the plug 10 so that the air in entering will flow past 85 the heating unit.

The device is especially useful in cold weather when the carbureter does not function efficiently, due to poor carburetion. In using the device, the switch 13 is closed to 90 energize the heating unit 8, and the valve 7 is closed, whereby the air within the chamber 5 will be heated. Then, after a few moments, the engine is started in the usual way, and the choke valve 3 is closed and the valve 7 opened, so that the heated air will 95 pass from the chamber 5 through the tube 6 into the carbureter. This will heat the carbureter and gasoline, so that the gasoline will vaporize and pass with the air through 100 the intake manifold, resulting in the engine starting quickly. The chamber 5 can be of sufficient size to hold considerable quantity of heated air, so as to assure of the starting of the engine even in extremely 105 cold weather, and the switch 13 can be left closed and the valve 7 left open until the engine is running perfectly. The valve 7 is then closed, and the switch 13 opened so that the carbureter will function in the ordinary way.

The device is intended particularly for

supplying heated air to a carbureter, but can be used similarly for other purposes.

Having thus described the invention, what is claimed as new is:—

- 5 1. The combination with an engine carbureter having a choke valve in the air inlet port, of a device for supplying heated air in starting the engine comprising an air chamber for holding a quantity of air to be supplied to the carbureter, a delivery tube leading from said chamber for conducting the air therefrom and connected to the carbureter at the inner side of said choke valve, a valve for said tube to establish and shut off the flow of air from said chamber to the carbureter at will, and an electrical heating unit in said chamber for heating the air therein before passing through said tube to the carbureter.
- 10 2. An air heater of the character described to be used with an engine carbureter, comprising an air chamber for holding a quantity of air to be delivered to the carbureter, an air delivery tube leading from said chamber

ber for conducting the air therefrom and 25 adapted for connection with the carbureter to supply the air thereto independent of the main air supply of the carbureter, a valve for said tube to control the flow of air from said chamber at will, and an electrical heating unit in said chamber for heating the air before being delivered through said tube.

3. An air heater of the character described comprising an air chamber, an air delivery tube leading from the upper portion thereof, and having a valve, a removable plug in the bottom of the casing, and an electrical heating unit mounted on said plug and removable therewith from the chamber, said plug having an air inlet port.

In testimony whereof I have signed my name to this specification in the presence of two subscribing witnesses.

OTIS W. MOORE.
